Primary Examiner — Kevin K Rudzinski*Assistant Examiner* — Clare Ann Gannon(74) *Attorney, Agent, or Firm* — Che-Yang Chen; Law Office of Michael Chen(57) **CLAIM**

The ornamental design for a multi-functional grass mat, as shown and described.

DESCRIPTION

FIG. 1 is a perspective view of the multi-functional grass mat showing my new design;

FIG. 2 is a top plan view thereof;

FIG. 3 is a bottom plan view thereof;

FIG. 4 is a front/rear elevational view thereof; and,

FIG. 5 is a left/right side elevational view thereof.

The broken lines depict portions of the article that form no part of the claimed design.
